J. V. D. PATCH, OF BROWNVILLE, NEBRASKA.

Letters Patent No. 80,209, dated July 21, 1868.

IMPROVEMENT IN ESCAPEMENTS.

The Schedule referred to in these Letters Patent and making part of the same.

TO ALL WHOM IT MAY CONCERN:

Be it known that I, J. V. D. PATCH, of Brownville, in the county of Nemaha, and State of Nebraska, have invented a new and improved Clock-Escapement; and I do hereby declare that the following is a full, clear, and exact description thereof, which will enable others skilled in the art to make and use the same, reference being had to the accompanying drawing, forming part of this specification.

The drawing is a front view of my invention.

The object of this invention is to obtain an equable and easy action of the pallets of a clock-escapement, or verge so called, and with the minimum power and friction.

The invention consists of a pendulum-rod, A, bearing the pallets a and b, affixed thereto in such a manner that they will act laterally upon the verge-wheel B, instead of on the top of the same, as usually made.

It further consists of the spring d affixed to the pendulum-rod A, and between the pallets shown, by the flexible and elastic nature of which spring the pallets are made to operate more equably and easily upon the verge-wheel. The spring d is suspended in the split stud e, affixed in the plate G.

I am aware that the pallets of pendulum-rods have been made to operate laterally upon the verge-wheel, (see patent granted to William Linden, November 26, 1867,) and therefore do not claim such a device broadly; but

What I claim as new, and desire to secure by Letters Patent, is—

The laterally-acting pallets a and b, spring d, and pendulum-rod A, all substantially as shown and described, in combination with the verge-wheels B and pendulum C of a clock, all as and for the purpose set forth.
